United States Patent Office

Des. 192,668
Patented Apr. 24, 1962

192,668

COMBINED LETTER OPENER AND PAPER WEIGHT

John M. Dollar, 1515 Bellevue, Seattle, Wash., assignor
of fifty percent to Martin J. Winninghoff, Seattle, Wash.

Filed Feb. 15, 1960, Ser. No. 59,388

Term of patent 7 years

(Cl. D74—10)

FIG. 1

FIG. 2

FIG. 3

FIG. 4

FIGURE 1 is an isometric view of a combined letter opener and paper weight showing my new design;

FIGURE 2 is a front elevational view thereof;

FIGURE 3 is an isometric view showing the sides opposite to that of FIGURE 1; and,

FIGURE 4 is a sectional view thereof taken on the line 4—4 of FIGURE 2.

I claim:

The ornamental design for a combined letter opener and paper weight, substantially as shown.
